JOHN A. HARRISON, CLIFFORD S. HARRISON, AND JOHN E. HARRISON, OF SHELBY,
MICHIGAN, ASSIGNORS TO HARRISON MFG. CO., OF SHELBY, MICHIGAN, A COR-
PORATION OF MICHIGAN.

METHOD OF MAKING CONTAINERS.

Application filed July 9, 1928. Serial No. 291,362.

This invention relates to the method of manufacturing wooden stave baskets.

The main objects of this invention are to provide an improved method of forming a straight-sided wooden stave basket, and to provide an improved method of converting a standard rounded-bottom wooden stave basket into a straight-sided square-bottomed basket.

10 Various illustrations showing the devices used in the different steps of the method are shown in the accompanying drawings, in which:

Fig. 1 is a view in elevation of a standard rounded-bottom bushel basket made of continuous wooden staves.

Fig. 2 is a view in vertical medial section of one of the forming dies which engages the rounded bottom of the basket.

20 Fig. 3 is a view in vertical medial section of the complementary straight-sided forming die upon which the rounded bottom basket is placed, a reformed basket being shown in position thereon and the die shown in Fig. 2 illustrated in dotted outline.

Fig. 4 is a view in elevation of a complete reformed straight-sided basket having a square bottom, which has been made from the basket illustrated in Fig. 1.

30 For a long period of time fruit and vegetables have been packed in rounded-bottom bushel baskets of the old standard type which have been manufactured for a great number of years. The general tendency at the present time, however, is to pack in straight-sided square-bottomed containers which can be stacked in shipping cars in a more stable manner and which have various other advantages.

40 In making such baskets of the newer type, the usual procedure is to manufacture the basket in the first instance with the wooden staves abruptly crimped at the bottom of the basket when the basket is first formed on a basket-making machine. There still exists quite a demand and call for the older type of rounded-bottom basket and, for a factory to be able to supply both types, it has been necessary for them to be equipped with the 50 two types of basket forming machines. These machines are large and expensive. Furthermore, in order to keep a stock on hand and to supply the needs of the trade, it has been necessary for the manufacturer to keep a stock

of both types of baskets, thereby carrying practically a double inventory of his product.

By use of the present method, the manufacturer need have only one type of basket-making machine, that type being the one for making the rounded-bottom basket of old style. Furthermore, he need carry in stock only the rounded-bottom type. In cases where the customer desires to have the straight-sided square-bottomed type of basket, the rounded-bottom baskets are taken from storage and, after being suitably softened around the bottom by the usual soaking in water, are then formed into the square-bottom straight-sided baskets on a relatively simple and inexpensive machine.

As illustrated in the drawings, a rounded-bottom wooden stave basket 1, as shown in Fig. 1 of the drawings, is placed on a straight-sided forming die 2, the die being such as to snugly fit the inside of the basket. A bottom hoop 3 is placed in a forming die 4 which has an annular rim 5 thereon for retaining the hoop 3 and holding the hoop against expansion or distortion. The central portion of the die 4 is provided with an annular plate 6 projecting from the inner face thereof and secured thereto by suitable means such as studs 7. Washers or shims 8 may be interposed between the inner face of the die and the under side of the plate 6 for adjustably positioning the plate with respect to the die.

70 The forming dies 2 and 4 are then moved toward each other in an axial direction by suitable machinery (not shown) thereby causing the plate 6 and inner face of the die 4 to engage the rounded bottom 9 of the basket 1. As the dies move together, the rounded bottom 9 is pressed inwardly, as shown in full lines in Fig. 3, and the staves of the basket are abruptly crimped at the points 10 and 11, and at the same time pressed out into engagement with the bottom hoop 3, the hoop 3 being held against breakage or distortion by the annular flange 5 of the die 4.

100 The bottom of the basket is pressed inwardly past the plane of the hoop 3. When the die 4 is retracted to its original position, the hoop 3 is retained on the basket 1 by the tendency of the bottom to spring outwardly toward its original position, i. e., the bottom having been buckled past center, it will be necessary for the diameter of the bottom to

be slightly increased before the bottom of the basket can return past the plane of the bottom hoop.

The basket is then removed from the die 2 and the hoop 3 stitched thereon by the usual form of wire stitching machine used in this industry.

By varying the distance which the plate 6 is spaced from the inner face of the die 2, the 10 capacity of the basket may be changed to a considerable degree.

Although but one specific method has been herein shown and explained, it will be understood that details of this method may be 15 varied within reasonable limits without departing from the spirit of this invention as defined by the following claims.

We claim:

1. The method of forming a straight-sided 20 concave-bottomed wooden stave container from a rounded bottom container which comprises the placing of a bottom hoop in a forming die, moving said die into engagement with the rounded bottom of said container to 25 form an abrupt peripheral crimp in said rounded bottom and to press it into engagement with said hoop.

2. The method of forming a straight-sided concave-bottomed wooden stave container

30 from a rounded bottom container which comprises the placing of a bottom hoop in a forming die, moving said die into engagement with the rounded bottom of said container to form an abrupt peripheral crimp in said rounded bottom and to press it into engagement with said hoop, said bottom being buckled inwardly past the plane of said hoop.

35 3. The method of forming a straight-sided concave-bottomed basket from a rounded bottom basket which comprises the placing of the rounded bottom basket on a straight-sided forming die, placing a bottom hoop in a complementary forming die and then pressing the two dies together to form an abrupt 40 peripheral crimp in said rounded bottom and to press it into engagement with said bottom hoop, said hoop carrying die buckling the bottom of said basket inwardly past the plane 45 of said bottom hoop, and then securing said hoop to said basket.

In testimony whereof we have hereunto set our hands at Shelby, Michigan, this 6th day of July, 1928.
